STATIONARY HUB CAP COVER

Benjamin Solow, Philadelphia, Pa.

Application November 1, 1954, Serial No. 466,035

6 Claims. (Cl. 301—108)

The present invention relates to a hub cap cover which is mounted on the hub cap of an automobile wheel or other vehicle wheel in such a manner that it is retained in a stationary position while the wheel is rotating during the course of travel of the vehicle. This permits an inscription, name, monogram, design or the like carried on the outer surface of the hub cap cover to be read by an observer notwithstanding the movement of the vehicle.

An object of the present invention is the provision of a hub cap cover of the aforesaid type of durable construction, which may be readily manufactured, and which may be mounted over a conventional hub cap without difficulty, and without requiring the use of special tools or equipment.

Another object of the present invention is the provision of a hub cap cover of the aforesaid type in which the symbol, design or inscription may be changed at the will of the user.

Further objects of the present invention will become apparent upon reading the following specification and referring to the accompanying drawings, in which similar characters of reference represent corresponding parts in each of the several views.

Figure 1 is a front elevational view of an embodiment of the present invention.

Figure 2 is a back elevational view of the embodiment of Figure 1, with the hub cap over which the cover is mounted shown in phantom line.

Figure 3 is a sectional view taken on line 3—3 of Figure 1.

Figure 4 is a sectional view of another embodiment of the present invention.

Referring initially to Figures 1 through 3, 10 designates a dome-shaped wheel hub cap of standard design provided on automotive vehicles.

The hub cap cover of the present invention designated generally by the numeral 11 includes a curved cover disc or plate 12 of sheet metal or the like, with a generally concavo-convex outer portion 13 and a dish-shaped or well-shaped center portion 14. The radially-outermost part of outer portion 13 is crimped or beaded so that the free edge of the disc 12 is not exposed to view.

A series of slits or perforations 15 defining an annulus is provided in the outer portion 13, spaced somewhat from the outer edge of the dish-shaped center portion 14. A symbol, letter, design or monogram-carrying disc or plate 16, preferably of polished chrome sheet metal, is retained in position on curved disc 12 by having peripheral tabs 17, which mate with slits 15, inserted through slits 15. The portion of tabs 17 in back of the disc 12 is offset, locking symbol-carrying plate 16 in position. The desired symbol-carrying plate 16 may be installed by the retail dealer, and a large and varied stock of such plates may be kept on hand.

A pair of bendable straps or bands 18, preferably of metal, is secured to the dish-shaped or well-shaped center portion 14 of disc 12 by means of centrally positioned bearing-eyelet or rivet 19. Straps 18 as shown in Figure

2

2 intersect at right angles to each other, being retained in this relationship by welds or the like in the region of overlap. Straps 18 are preferably scaled or graduated, as at 20, to permit proper central alignment of the hub cap cover 11 over the vehicular hub cap 10.

5 A weight 21, such as a metal rod or the like, is welded or otherwise secured to the back of disc 12, and may be disposed in an axial plane perpendicular to the axial plane of the pivot, with the center of the longitudinal axis 10 of the weight lying on a line passing through the geometrical center of disc 12.

10 Sufficient clearance is provided in the opening in dish-shaped center portion 14 through which eyelet 19 passes to permit disc 12 to freely pivot about eyelet 19.

15 The mounting and operation of the hub cap cover of the present invention is as follows:

20 The hub cap cover 11 is clamped over the vehicular hub cap 10 by passing straps 18 over the rim edge of hub cap 10 and friction fitting the hub cap 10 into its operative position on the vehicular wheel. In this position, straps 18 are anchored by hub cap 10. The graduations 20 on straps 18 permit accurate centering of the hub cap cover 11 over the vehicular hub cap 10.

25 Since hub cap cover 11 is free to rotate about eyelet 19, the action of gravity on weight 21 serves to retain the hub cap cover 11 in aligned position with the weight 21 undermost, notwithstanding rotation of the wheel during the motion of the vehicle.

30 In the embodiment shown in Figure 4, the rim 22 of the dish-shaped center portion 14a of disc 12a projects beyond the plane of outer portion 13a to form a locking seat for symbol-carrying plate 16a, which is slipped over rim 22 and frictionally retained in position. Symbol-carrying plate 16a can be removed readily from disc 12a 35 by being pried therefrom by means of a screwdriver, or the like, inserted between the free edge of symbol-carrying plate 16a and the front surface of the outer portion 13a of disc 12a adjacent rim 22. Rapid replacement of symbol-carrying plate 16a permits the user of the vehicle 40 to substitute desired symbols, letters, words or designs at will.

35 While I have illustrated and described the preferred embodiments of my invention, it is to be understood that I do not limit myself to the precise constructions herein disclosed and the right is reserved to all changes and modifications coming within the scope of the invention as defined in the appended claims.

40 Having thus described my invention, what I claim as new, and desire to secure by United States Letters Patent is:

45 1. A non-rotatable hub cap cover for the hub cap of a vehicle including a cover plate, a pivot in the cover plate at the center portion thereof with its axis normal to the plane of the adjoining portion of the cover plate, strap 50 means carried on said pivot in back of said cover plate, said strap means constructed and arranged to be anchored by the hub cap of the vehicle, a weight fixedly secured to the cover plate, locking means adjacent the center of the cover plate for removably receiving a symbol-carrying disc on the front surface of said cover plate, and a symbol-carrying disc constructed and arranged to be operatively interlocked with said locking means and to be carried over the front surface of the center portion of the cover plate thereby covering the pivot.

55 2. A non-rotatable hub cap cover for the hub cap of a vehicle including a generally concavo-convex cover plate having a dish-shaped center portion, a pivot in the center of the dish-shaped center portion with its axis normal to the plane of the adjoining portion of the cover plate, a plurality of flexible straps, retained in spaced relationship 60 to each other and carried on said pivot and juxtaposed to

the concavo surface of the cover plate and the floor of the dish-shaped center portion, said straps having a graduated scale on the surface facing the cover plate whereby the cover plate may be retained centered above the hub cap of the vehicle with the straps anchored by the hub cap, a weight fixedly secured on the concavo surface of the cover plate, said weight being disposed in an axial plane normal to the axial plane of the pivot, locking means adjacent the dish-shaped center portion of the cover plate for removably receiving a symbol-carrying disc, and a symbol-carrying disc constructed and arranged to be operatively interlocked with said locking means and to be carried over the convex portion of the cover plate covering the dish-shaped center portion and the pivot.

3. A non-rotatable hub cap cover for the hub cap of a vehicle including a generally concavo-convex cover plate having a dish-shaped center portion, a pivot in the center of the dish-shaped center portion with its axis normal to the plane of the adjoining portion of the cover plate, a plurality of flexible straps, retained in spaced relationship to each other and carried on said pivot and juxtaposed to the concavo surface of the cover plate and the floor of the dish-shaped center portion, said straps being constructed and arranged to be anchored by the hub cap of the vehicle, a weight fixedly secured on the concavo surface of the cover plate, perforations in the cover plate adjacent its dish-shaped center portion, a symbol-carrying disc having anchoring projections adapted to be received in said perforations, whereby the body of said symbol-carrying disc may be operatively carried in front of the convex surface of said cover plate, spaced from the floor of the dish-shaped center portion.

4. A non-rotatable hub cap cover for the hub cap of a vehicle including a generally concavo-convex cover plate having a dish-shaped center portion, a pivot in the center of the dish-shaped center portion with its axis normal to the plane of the adjoining portion of the cover plate, a plurality of flexible straps, retained in spaced relationship to each other and carried on said pivot and juxtaposed to the concavo surface of the cover plate and the floor of the dish-shaped center portion, said straps being constructed and arranged to be anchored by the hub cap of the vehicle, a weight fixedly secured on the concavo surface of the cover plate, the rim of said dish-shaped center portion projecting out of the plane of the convex surface and forming a frictional locking seat for a symbol-carrying disc, a symbol-carrying disc having an upwardly and inwardly projecting edge, said edge constructed and arranged to be removably mounted on said frictional locking seat.

5. A non-rotatable hub cap cover for the hub cap of a vehicle including a generally concavo-convex cover plate

having a dish-shaped center portion, a pivot in the center of the dish-shaped center portion with its axis normal to the plane of the adjoining portion of the cover plate, a plurality of flexible straps, retained in spaced relationship to each other and carried on said pivot and juxtaposed to the concavo surface of the cover plate and the floor of the dish-shaped center portion, said straps having a graduated scale on the surface facing the cover plate whereby the cover plate may be retained centered above the hub cap of the vehicle with the straps anchored by the hub cap, a weight fixedly secured on the concavo surface of the cover plate, said weight being disposed in an axial plane normal to the axial plane of the pivot, and so positioned that when the hub cap cover is operatively mounted on the hub cap, it does not engage the hub cap, the rim of said dish-shaped center portion projecting out of the plane of the convex surface and forming a frictional locking seat for a symbol-carrying disc, a symbol-carrying disc having an upwardly and inwardly projecting edge, said edge constructed and arranged to be removably mounted on said frictional locking seat, said symbol-carrying disc covering the dish-shaped center portion and the pivot when its edge is mounted on said frictional locking seat.

6. A non-rotatable hub cap cover for the hub cap of a vehicle including a generally concavo-convex cover plate having a dish-shaped center portion, a pivot in the center of the dish-shaped center portion with its axis normal to the plane of the adjoining portion of the cover plate, a plurality of flexible straps, retained in spaced relationship to each other and carried on said pivot and juxtaposed to the concavo surface of the cover plate and the floor of the dish-shaped center portion, said straps having a graduated scale on the surface facing the cover plate whereby the cover plate may be retained centered above the hub cap of the vehicle with the straps anchored by the hub cap, a weight fixedly secured on the concavo surface of the cover plate, said weight being disposed in an axial plane normal to the axial plane of the pivot, and so positioned that when the hub cap cover is operatively mounted on the hub cap, it does not engage the hub cap, a plurality of perforations in the cover plate adjacent the dish-shaped center portion, a symbol-carrying disc having a plurality of tabs mating with said perforations, said symbol-carrying disc covering the dish-shaped center portion and the pivot when its tabs are retained in said perforations in said cover plate.
